UNITED STATES PATENT OFFICE.

JOHN B. DAYFOOT AND HARRY G. STEDMAN, OF CAMBRIDGE, MASSACHUSETTS, ASSIGNORS TO IVERS & POND PIANO COMPANY, OF BOSTON, MASSACHUSETTS, A CORPORATION OF MASSACHUSETTS.

PEDAL FOR PIANOS.

SPECIFICATION forming part of Letters Patent No. 690,362, dated December 31, 1901.

Application filed April 15, 1901. Serial No. 55,801. (No model.)

To all whom it may concern:

Be it known that we, JOHN B. DAYFOOT and HARRY G. STEDMAN, citizens of the United States, residing at Cambridge, in the county of Middlesex, State of Massachusetts, have invented a certain new and useful Improvement in Pedals for Pianos, &c., of which the following is a specification, reference being had therein to the accompanying drawings.

10 In the drawings, Figure 1 shows in plan the pedals of a piano and the mounting therefor with the cap-block removed and represents one embodiment of the invention. Fig. 2 is a view in section on line 2 2 of Fig. 1 with the 15 cap-block in place. Fig. 3 is a plan view of certain details, as hereinafter described. Fig. 4 is a view in section on line 4 4 of Figs. 1 and 2. Figs. 5, 6, and 7 illustrate modifications.

The invention has relation more especially 20 to the means of mounting pedals in pianos and other musical instruments. It has for its main object to produce an improved construction which shall enable the pedals of a piano or other instrument to be applied and properly secured in operative position and to be 25 removed when necessary with greater convenience and rapidity than in the case of the constructions heretofore in general use.

Having reference to the drawings, portion 30 of the front casing 1 of a piano is indicated in dotted lines in Figs. 1 and 2 and portion of the bottom thereof is shown at 2, Figs. 2 and 4. The block or pedestal with which the inner portions of the pedals are connected is 35 shown at 3. It is formed with notches or recesses 31 31 in its upper part for the reception of the said portions of the pedals, these last being entered between the upwardly-projecting portions 4 4 at the opposite sides 40 of the said notches or recesses. Upon the block or pedestal 3 is placed a cap-block 8, which is notched or recessed in its under side to correspond with the block or pedestal 3, as shown clearly in Figs. 2 and 4. The said 45 portions 4 4 are grooved in their upper surfaces to receive the pivotal pin or pins of the pedals. In the preferred embodiment of the invention a separate pivotal pin 7 is provided for each pedal, it extending trans-

versely across the notch or recess for such 50 pedal in the block or pedestal 3 and having its end portions located in the grooves at opposite sides of the said notch or recess. The said grooves constitute bearings for the said separate pivotal pins, the said end portions constituting journals and being surrounded by 55 suitable felt or equivalent bushings 15 15, as shown best in Fig. 1.

Heretofore it has been the practice to mount the series of pedals in a piano or the like 60 upon a single rod or long pin carried by a suitable support. This has the disadvantage that the movement of the respective pedals around the said rod or pin is productive of squeaking and noise. It has the further disadvantage that if for any reason the bearings of the respective pedals upon the said rod or pin should be too tight and bind the movement of one pedal will either twist the pin or rod or cause one or all the others to be moved. 65 By the use of a separate pivotal pin for each pedal the pedals are rendered entirely independent of one another in their movements, and by furnishing the journals of the said separate pins within the bearings therefor 70 with bushings, as just noted, and clamping the respective pins to the corresponding pedals, as noted hereinafter, all disagreeable noise and the like are obviated.

In the present instance the cap-block and 75 pedestal are fixed together and to the bottom 2 of the casing by means of wood-screws 9 9. (Shown best in Figs. 2 and 4.)

5 5 5 are the pedals, and 19 19 19 are the connections extending upwardly therefrom. 80 Each pedal is provided with a seat to receive and fit the pivotal pin and with a movable cap to lock the pivotal pin and seat together. The form, arrangement, and construction of the seat and cap may be varied within certain 85 limits without involving a departure from the invention. Preferably the seat is located at the top of the pedal, and more particularly when a separate pivotal pin is employed for each pedal is constructed with an angular 90 notch adapted to receive the body of the pivotal pin. The movable cap usually is formed as a plate applied to the pedal and arranged to 95

receive the pivotal pin between the same and the seat. The seat and cap press firmly against opposite surfaces of the pivotal pin, so that there is no looseness or vibration. In

- 5 Fig. 2 the seat is constituted by the angular notch 10 in the top of the rear extremity of the pedal, and the cap-plate 11 is acted upon by an adjusting-screw 12, by means of which the said cap-plate and pedal are drawn together upon the pivotal pin. By compressing the said parts tightly upon the pivotal pin the latter may be locked with the pedal, so as to move in unison with the pedal, and its end portions or journals will turn in the bearings which are formed in the portions 4 4 of the block or pedestal 3. When it is desired to insure against relative movement of the pedal and pin, which is preferred in practice, the best results are attained by forming one 15 of the shoulders of the notch with an acute or right angle in order that the sharper angle may take a better grip of the pivotal pin. This is illustrated by Fig. 2, in which one of the said shoulders is formed with an acute 20 angle. However, in the case of a notch having both of its shoulders formed with obtuse angles, as in Fig. 7, if the notch is bushed, as at 10°, as well as the bearings for the ends of the pivotal pin 7, it will not be objectionable 25 30 if the said pin is capable of turning in both the notch or seat and the bearings. In some embodiments of the invention the notch may be rectangular, as at 16 in Fig. 5.

To hold the cap-plate 11 from turning, the 35 front end thereof is arranged to take against a shoulder 14 on the top part of the pedal. (See Figs. 2 and 5.) By providing this shoulder it is rendered unnecessary to employ more than a single screw 12 in connection with the 40 cap-plate 11. The best results are attained in practice by making the shoulder 14 undercut, as in Fig. 2, and beveling the end of the cap-plate 11 to enter the angle formed between the said shoulder and the adjacent portion 45 of the top of the pedal at the rear of the shoulder. The undercut shoulder of the pedal holds the adjacent end of the cap-plate down in place, keeping such end from rising above the shoulder, and prevents the cap-plate from 50 becoming displaced laterally relative to the pedal after screw 12 has been loosened somewhat. It prevents the said end from rising as the screw 12 is tightened and causes the cap-plate to move upon such end under the 55 shoulder as upon a fulcrum, enabling thereby the cap-plate to be tightened upon the pivot-pin to greater advantage.

The rear end of the cap-plate 11 is arranged to project at all times from the adjacent portion 60 of the pedal 5 in such a manner as to facilitate the entrance of the pivotal pin between the cap-plate and the pedal. In Figs. 2 and 5 the said end of the cap-plate projects beyond or overhangs the extreme rear end of the pedal, so that in performing the operation of placing the pedal in position the rear portion of the pedal may be pushed through

the opening 1^a, Fig. 2, in the front portion 1 of the casing until the projecting portion of the cap-plate 11 passes above and rests upon the pivotal pin 7. Thereby the pedal is guided, so that without further assistance the seat and pivotal pin may be caused to assume their proper relative positions, after which the cap-plate may be tightened up by turning 70 the screw 12 by means of a screw-driver applied from above. For the purpose of facilitating access to the head of the screw 12 the front of the cap-block 8 is notched or cut away above the same, as at 13, (see more particularly Fig. 3,) to admit the necessary tool. In cases where the pedal is formed with a portion thereof projecting to the rear of the seat 10, as in Fig. 6, in which latter the connection 19 is united with the pedal at the rear of 80 the pivotal pin 7, the top surface of the pedal 5 will be shaped to cause the rear end of the cap-plate 11 to project or stand normally a sufficient distance from the proximate surface of the pedal to facilitate the passage of the 90 pivotal pin 7 beneath the said rear end of the cap-plate 11. In this case in the operation of introducing the pedal into place the upper surface thereof at the rear of the seat 10 will be caused to press against the under surface of the pivotal pin 7, and then on pushing the pedal farther to the rear the rear end of the cap-plate 11 will pass above the pivotal pin, the latter finding its way readily into the notch 10. 100

When it is desired to remove the pedal from its pivotal support, this may readily and quickly be effected simply by loosening the screw 12 sufficiently to enable the cap-plate 11 to move far enough away from the top of the rear portion of the pedal to permit the pivotal pin to pass out between the cap-plate and the pedal. The operation of replacing the pedal may be as conveniently and quickly performed in the manner already set forth 110 above.

If the rear end of the cap-plate 11 were flush with the pedal, it would be necessary to use some tool to lift up said end in order to facilitate the passage of the pivotal pin between the said cap-plate and the pedal. By causing the rear end of the cap-plate to project normally a sufficient distance from the pedal to enable said end to seat itself upon the upper side of the pivotal pin when the 120 pedal is pushed rearwardly into place the use of the tool for the purpose noted is rendered unnecessary, since the operation of applying the pedal properly to its pivotal support is facilitated by feeling with the projecting cap-plate for the pivotal pin. 125

Should for any reason it be desired to effect adjustment or shift of the pedal transversely within its recess or notch in the block or pedestal 3, this may be provided for conveniently 130 at the time of assembling the said block or pedestal, the pivotal pin 7, and the cap-block 8 by placing on the said pin three, four, or more washers 71, the said washers being

such as usually are employed for sound-deadening purposes between opposite sides of a pedal and its mounting. If at any time the adjustment of the pedal transversely should be found necessary, it may be effected simply by loosening the screw 12 sufficiently to permit withdrawal of the pedal from its pivotal pin, then locating or setting the washers on the pin, so as to place equal or unequal numbers of washers at the opposite sides of the recess, according to the position which it is desired to give to the pedal, then replacing the pedal in the manner already explained, and then tightening up the screw or other adjusting device which is employed in connection with the cap-plate 11. It will be obvious that in practice other convenient and known adjusting devices for the cap-plate 11 may be employed in lieu of the screw 12.

20 What we claim is—

1. In combination, a support containing bearings, a pivotal pin carried by said support and turning in the bearings thereof, a pedal having a seat which detachably fits the said pivotal pin, the movable cap-plate on said pedal, and means to compress said cap-plate against said pivotal pin to clamp the pedal to the said pin and compel them both to turn in unison.
2. In combination, a support containing bearings, a pivotal pin carried by said support and turning in the bearings thereof, a pedal having a seat which detachably fits the said pivotal pin, the movable cap-plate on said pedal, and the clamping-screw accessible from above and acting upon said cap-plate to clamp the pedal to the pin and compel them both to turn in unison.
3. In combination, the pivotal pin, the support therefor, the pedal having the seat which

receives the said pivotal pin, and the movable cap-plate having the end thereof projecting at all times clear of the pedal to guide the pin into the seat in assembling the parts, substantially as described.

4. In combination, the pivotal pin, the support therefor, the pedal having the seat which receives the said pivotal pin, the movable cap-plate having the end thereof projecting normally clear of the pedal to enable said end to seat itself upon the upper side of the pivotal pin when the pedal is pushed rearwardly into place, whereby to guide the pin beneath the same in assembling the parts, and the adjusting device accessible from above, substantially as described.

5. In combination, the support, the pivotal pin carried thereby, the pedal having the seat which receives the said pivotal pin and adjacent the same the undercut shoulder, the cap-plate having one end thereof seated under the said shoulder, and means to clamp the said cap-plate upon the pivotal pin.

6. In combination, the support provided with bearings for a series of pivotal pins, a plurality of pivotal pins applied to the said support and having the journals thereof bushed as described, and the plurality of pedals each having a seat which receives the corresponding pivotal pin, a cap-plate, and means to compress the said cap-plate against the pedal to clamp the pedal and pivotal pin together.

In testimony whereof we affix our signatures in presence of two witnesses.
